CARRYING CASE

George H. Hake, Alden, N. Y., assignor to Niagara Plastic Molds, Inc., Buffalo, N. Y., a corporation of New York
Application October 31, 1955, Serial No. 38,646

Term of patent 14 years

(Cl. D58—12)

Fig. 1

Fig. 2.

Fig. 3.

Fig. 4

Fig. 5.

Fig. 1 is a front elevational view of a carrying case, showing my new design.

Fig. 2 is an end view thereof taken from the right of Fig. 1.

Fig. 3 is a top plan view thereof.

Fig. 4 is a bottom plan view thereof.

Fig. 5 is a vertical sectional view thereof taken along the line 5—5, Fig. 1.

The rear and end views of the design not shown are the same as the front and end views, respectively, shown.

I claim:

The ornamental design for a carrying case, substantially as shown and described.
